UNITED STATES PATENT OFFICE.

FRANCIS A. WINSLOW, OF CHICAGO, ILLINOIS, ASSIGNOR TO THE WINSLOW BROTHERS COMPANY, OF ILLINOIS.

DOOR FOR ELEVATORS OR OTHER INCLOSURES.

SPECIFICATION forming part of Letters Patent No. 549,989, dated November 19, 1895.

Application filed January 14, 1895. Serial No. 534,793. (No model.)

To all whom it may concern:

Be it known that I, FRANCIS A. WINSLOW, a citizen of the United States of America, residing at Chicago, in the county of Cook and State of Illinois, have invented certain new and useful Improvements in Doors for Elevators or other Inclosures, of which the following is a specification.

My invention relates to sliding doors of the above class which are arranged in pairs and which it is desirable to open or close together. Such doors are used upon elevator-shafts and similar constructions when a single door does not give a sufficient opening.

The purpose of the invention is to provide a suitable connection between the two doors whereby the opening or closing of one will open or close the other, and, furthermore, as an additional purpose the invention furnishes a construction which enables the entire opening in which the doors travel back and forth to be cleared for the passage of large and bulky freight.

The invention is illustrated by means of five figures, of which—

Figure 1 is a side elevation of a pair of elevator-doors and a portion of the inclosure between the two, said view being taken from the interior of the elevator-shaft and showing the doors in their closed position. Fig. 2

is a similar view of two pairs of elevator-doors, the view being taken from the same direction, one of said pairs of doors being shown in the ordinary open position and the other pair being shown in their position when the entire double opening is cleared for the passage of freight. Fig. 3 is a vertical section in line 3 3 of Fig. 1, the parts being shown on a much larger scale and it being

therefore necessary to break away certain of the unimportant portions to bring the view within the limits of the sheet. Fig. 4 is a horizontal section of line 4 4, Fig. 3, the portions being shown upon the same scale and being also broken away at certain points to condense the important portions; and Fig. 5 is a horizontal detail section in line 5 5 of Fig. 1.

Looking at Fig. 1, two doors are shown at A A' within an opening inclosed by a common sill B, a common lintel C, and the two jambs D E. The opening is substantially three

times the width of one of the doors, and the space between the doors when closed is occupied by a grille F, which is adapted to be removed by means hereinafter described. Upon the lintel C is supported a double track G G', upon which travel rollers a a a' a', journaled in hangers a² a² a³ a³, which carry the two doors A A'. Upon the sill B are guides b b' for the two doors, so that when the same are thrown backward in front of the grille F they will pass the one in front of the other without striking together. At the middle point of the sill B an upright bar H is removably secured by means of straps h h', the former of which forms a socket for the end of the bar, and the latter, which is in fact a latch, is pivoted at h² and hooked over a screw h³. This latch or hook is shown as open in the right-hand door of Fig. 2. The top of the bar H, which reaches as high as the ordinary latch, has pivoted to it the middle portion of a lever I, curved vertically in opposite directions at its opposite ends and pivoted to the similarly-curved ends of two links or arms J K, extending across the two doors and pivoted to the same at their outside edges. The curvature of the ends of the middle lever and the links throws the pivotal points out of line, so that while the main portions of the lever and links are substantially horizontal the pivotal points of the same are thrown sufficiently out of line to avoid locking the same against an end thrust. The left-hand door is shown as provided with an ordinary gravity-latch L, operated by a vertical rod M, having at the top a knob N.

In opening the doors the knob N is first raised and then shoved toward the right, forcing the levers in the directions shown by the two arrows and consequently opening the right-hand door to the same extent as the left-hand. In closing the door the operation is reversed, and this link-and-lever connection which has just been described makes the operation of the two doors as simple as the operation of a single door. As the doors are opened, they pass one in front of the other and as they are closed they strike against stops O P Q R. Of these the stop O consists of a bracket (see Fig. 5) hinged to a plate o, fastened to the jamb E, so that it can be swung

into the position shown in dotted lines in the figure to allow the door to slide past it when desired. The stops Q R consist of plates pivoted to the tracks G G' on the opposite sides 5 from the hangers $a^2 a^3$, and having pins q , which may be thrust into or withdrawn from holes q' , extending through the tracks, so that the pin may be interposed in the path of the hanger as it moves back and forth. These pivoted stops are provided so that they may be 10 thrown out of operation when it is desirable to move the doors to the right beyond the closed position of the door A'.

The central grille F is held in position by 15 pins f , extending into sockets in the sill B, and by thrust-bolts f' , entering sockets c in the lintel C.

When it is necessary to use the entire opening between the jambs, the doors are opened 20 into the position shown in Fig. 2, the hook or latch h' is disengaged from the screw h^3 , and the bar H is lifted from the socket h and swung upward into a hook x at the top of the doors. The stops O Q R are then thrown 25 out of operative position and the doors pushed to the right into the position shown in Fig. 2. The thrust-bolts f are then withdrawn and the grille F taken up, leaving the entire opening free from obstruction.

30 I claim as new and desire to secure by Letters Patent—

1. The combination with a pair of sliding doors and their inclosure, of a horizontal lever pivoted between its ends upon a pivot 35 stationary with reference to the inclosure, said lever being curved upward at one end and downward at the other and a pair of horizontal links pivoted, respectively at one

end to the respective doors and curved at the other end to correspond with the adjacent end 40 of the lever and pivoted thereto, whereby when the levers and links are extended they may lie substantially in the same horizontal line and yet the pivotal points between the lever and the links may be thrown out of 45 said line to prevent the lever from locking the doors; substantially as described.

2. The combination with the doors, A, A', and their inclosure, of the bar, H, removably secured to the inclosure, the lever, I, pivoted 50 between its ends to the bar, the links, J, K, pivoted, respectively, to the two doors at one end and at the other end to the opposite arms of the lever, I, and the hook, or rest, x , secured to one of the doors and adapted to 55 sustain the bar, H, when detached from the inclosure; substantially as described.

3. The combination with the sill, jambs and lintel of the inclosure, of the removable grille, F, centrally located within the opening, the 60 tracks, G, G', supported from the lintel, the doors, A, A', provided with a link and lever connection mounted upon a pivot suitably supported from the inclosure, but detachable therefrom to enable the two doors and their 65 connecting devices to be moved laterally from the opening and a series of door stops provided with means whereby they may be thrown out of operation to enable the doors to be pushed beyond their normal limit of 70 motion; substantially as described.

FRANCIS A. WINSLOW.
